(57) **CLAIM**

I claim the ornamental design for a trigger guard, as shown and described.

DESCRIPTION

FIG. 1 is a perspective view of a trigger guard according to the invention.

FIG. 2 is a side elevation view of the trigger guard depicted in FIG. 1.

FIG. 3 is a side view of the trigger guard depicted in FIG. 1, opposite the side view of FIG. 2.

FIG. 4 is a front elevation view of the trigger guard depicted in FIG. 1; and,

FIG. 5 is a bottom plan view of the trigger guard depicted in FIG. 1.

The broken lines illustrate portions of the trigger guard which form no part of the claimed invention.
